LINE CASTING AND COMPOSING MACHINE

Louis M. Potts, Evanston, Ill., assignor to Teletype Corporation, Chicago, Ill., a corporation of Delaware

Original application January 2, 1932, Serial No. 584,387. Divided and this application May 10, 1933, Serial No. 670,251

10 Claims. (Cl. 199—29)

This invention relates to linecasting and composing machines and more particularly to mechanism for effecting their automatic operation.

The present application is a division of copending application Serial No. 584,387, filed January 2, 1932.

The object of the present invention is to provide, in a linecasting and composing machine controlled by a signal responsive device having an assembling block for receiving matrices during the process of line composing at either of two levels dependent upon the position of a shiftable rail, mechanism for temporarily arresting the activity of the composing mechanism while the rail shift function is being consummated and for delaying the rail shift function a sufficient period of time to permit previously released matrices to settle and assume their assembled position.

In the course of the following description, the linecasting and composing machine including all of the principal parts heretofore provided solely for manual control purposes shall be referred to hereinafter as the principal machine; the signal responsive unit whereby the several functions of the principal machine are automatically controlled shall be referred to as the automatic control unit, and the mechanism for shifting the shiftable rail of the assembling block under the control of particular signals, shall be referred to as the rail shift mechanism.

As set forth in the parent application, the automatic control unit comprises generally, a record reader mechanism which responds to the perforations of a control tape or to corresponding electrical impulses, and a selector mechanism which is operated by the settings of the aforesaid record reader. In accordance with each selection received from a control signal, a corresponding one of a plurality of selectable elements is moved into a selective or conditioning position, after which timed actuating mechanism deriving its power from the principal machine, functions to move the selected one of the elements, causing the latter to complete the particular function for which it was selected. Of the plurality of elements, certain ones are adapted to release corresponding matrices from the storage magazine of the principal machine, and certain other ones are adapted to execute special functions incident to line composition and casting operations such as, for example, the movement of the shiftable rail.

In accordance with a preferred practice of the present invention, a pair of selectable elements is provided, each of which may be conditioned in response to an individual signal delegated to it.

Upon the subsequent movement of the selectable element, it is made to release an associated clutch trip controlled by a pair of bell cranks, thereby permitting the engagement of a driving communication to a driven apparatus which is rendered effective at a reduced frequency of performance so as to effect a delay, while also momentarily suspending the further performance of line composition so that no additional matrices may be released until the assembling block and rail are in position to properly receive them. The release of each bell crank permits the engagement of the clutch mechanism for a half revolution, where it comes under the control of the other of said bell cranks which again causes the disengagement of the clutch. The driven mechanism comprises a shaft which carries a cam, and as the shaft may be arrested in two positions, so the cam may be stopped with either its apex or high portion in engagement with its follower roller or its nadir or low portion in engagement therewith. The follower roller is carried by a bell crank which, in turn, engages a depending shifting arm which is directly articulated to the shiftable rail in the assembling block. When the elevator with which the assembling block is integrally formed is in its down or composing position, the depending lever is in cooperative relation with the bell crank last mentioned, and in accordance with the position of said bell crank, causes the rail to assume one or the other of its two shiftable positions.

A better understanding of the present invention will be obtained from the following description, taken in conjunction with the accompanying drawings in which,

Fig. 1 is a general perspective view of a standard line-casting and composing machine having an automatic control unit applied thereto, of which certain parts are broken away to reveal the obscured parts of the selector mechanism;

Fig. 2 is a detailed front elevation illustrating the assembling block shiftable rail and a portion of the rail shift mechanism associated therewith;

Fig. 3 is a perspective view of the assembling block showing a plurality of matrices assembled both in the bold and roman positions;

Fig. 4 is a detailed sectional view with parts broken away, taken approximately on line 4—4 of Fig. 2, showing the delay mechanism associated with the rail shift mechanism;

Fig. 5 is a detailed sectional view taken approximately on line 5—5 of Fig. 2, illustrating the contour of the rail shift operating cam, and

Fig. 6 is a fragmentary detailed elevation of a modified shiftable rail that may be electrically

controlled directly from a pair of selectable elements.

In the following explanation, more particular description will be given of the mechanism which forms the subject matter of the present invention, reference being had to the parent application for a complete understanding of the general operations of linecasting and composing machines as well as to the automatic control unit.

10 Considering more particularly the accompanying drawings in which like reference characters designate similar parts throughout, attention is directed to Figs. 1 and 2, wherein is illustrated, generally, the elevator casting 11, having integrally formed therewith the assembling block 12. As better illustrated in Fig. 3, the assembling block comprises a pair of side walls 13 and 14, each having integrally formed a lower supporting rail 15, upon which may rest the bottom lugs 16 of the matrices 17 when the latter are received in the lower or roman position. As viewed in Figs. 1 and 2, the right-hand portion of the assembling block 12 is the end at which selected matrices are received, and will be designated hereinafter as the ingress portion. A shiftable rail 18, which may be formed of sheet metal as indicated, affords a rail section which protrudes through the wall 14 of block 12 and presents its innermost edge 19 parallelly with respect to and 30 slightly above the lower rail 15 of wall 14.

As illustrated, rail 18 is somewhat shorter than the wall 14, and is provided with a depending lug 21 to which is secured a spring 22, having its other end fastened to the assembling block and tending normally to maintain rail 18 in its left-hand position so as to afford a clearance 23 at its ingress portion. The opposite end of rail 18 is provided with an extensive depending wall 24 to which is attached one end of a lever 25, pivoted 40 at 26 to the elevator 11, and which is provided at its other end with a transversely extending portion 27, beveled as at 28.

As described in the parent application, the automatic control unit is provided with a principal operating shaft 29 which, although not shown in the accompanying drawings, consists of two parts, the first of which is continuously rotatable, and the second of which is driven from the first through a clutch controlled by the clutch controlling mechanism indicated generally by 31 in Fig. 4, which is controlled by a start magnet 32, located in a control circuit 33, in which are also located several circuit breakers 10, 20 and 34, each of which relates to an associated mechanism 55 which may, under certain conditions, open the control circuit 33 for thereby arresting the continued rotation of the driven portion of shaft 29. Among these several circuit breakers, the one indicated 34 particularly concerns the present invention, and comprises a pair of contact springs inclined to remain apart, but pressed into contractual relationship with each other by either of a pair of insulated apices 35, carried upon a cam 36, which is secured to and rotatable with the driven portion of a shaft 37, generally referred to hereinafter as the rail shift operating shaft.

The operating shaft 29 receives its power preferably from a constantly rotating source associated with the principal machine through suitable belt and pulley means 38, indicated in the background of Fig. 4. A pinion 39, keyed to the continuously rotatable portion of shaft 29 is adapted to drive an associate gear 41 carried by an intermediate shaft 42, while the latter, by 75 means of a similar pinion 43, likewise imparts a

corresponding motion to an associate gear 44, secured to the driving portion of shaft 37. The several gears just described will be understood to constitute a reduction gear train for imparting a delayed or retarded movement to driven shaft 37 5 as compared with the movement received by the driving shaft 29 from the principal machine.

Among the several elements 40, which are individually selectable by the code bars 50 as described in the parent application, are a pair indicated by 10 the numerals 45 and 46 which are generally located above a tooth clutch 47, which connects the driving and driven portions of shaft 37. Element 45 carries a spring pressed pawl 48, Fig. 4, which cooperates with one arm of bell crank 49, pivoted at 51, the other arm of which is provided with a beveled orifice 52, which registers above and in radial alignment with the driven portion 53 of clutch 47. The other element 46 carries a similar pawl 54 which cooperates with bell crank lever 15 55, pivoted at 56, and likewise provided in its corresponding arm with an orifice 52, having a beveled side wall similar to and radially opposite the first described orifice of bell crank lever 49. During the normal condition of elements 45 and 46, their respective pawls 48 and 54 engage the associated arms of their bell crank levers, as illustrated in Fig. 4, but permit the latter to remain in their effective position; that is, having their clutch engaging arms adjacent to and capable of 20 encountering a lug 57 also suitably beveled and integrally formed with the driven portion 53 of clutch 47. This slug, upon being engaged by the beveled surface of the arms of one or the other of bell cranks 49 and 55, is adapted to be retracted 35, thereby causing the driven portion 53 of clutch 47, as viewed in Fig. 2, to be shifted leftwardly, so that its teeth 58 will come out of engagement with the teeth 59 of driving portion 61. It should also be understood that driven portion 53 is conventionally keyed to the hub of cam 62 so as to 40, permit longitudinal movement to the former for the purpose of affording clearance to allow for the aforescribed clutch disengagement and re-engagement operations.

A spring 63, confined between cam 36 and a shoulder portion of driven member 53, tends to urge the latter into engagement with its driving portion 61, but this engagement is prevented by the frictional torque which maintains the lug 57 50 in the foremost portion of the inclined surface of orifice 52 of either arm 49 or 55.

During the engagement of lug 57 with either bell crank arm 49 or 55, one or the other of apices 35 will engage the contacts 34 so as to maintain 55 the control circuit 33 closed so far as this particular circuit breaker is concerned, but during the interval when lug 57 is proceeding from one position to the other, the apices 35 will be withdrawn from said contacts, permitting the latter 60 to remain apart and thereby open the control circuit 33 and arrest the further rotation of the driven portion of shaft 29, which controls the record reader mechanism 30, as described in the parent application. Thus it will be understood 65 that during the rail shift operation under control of operating shaft 37, which, as previously described, has its rotation delayed or retarded with respect to the rotation of shaft 29, the performance of the record reader will be arrested pending the 70 completion of the rail shift operation, thereby preventing the release of any matrices during the interim, but that normal composition is restored upon the completion of the rail shift movement in either direction. The driven portion 53 carries 75.

with it cam 62, the contour of which will be more clearly understood from Fig. 5. This cam, when in position to effect roman line composition, has its apex 64 pointed downwardly, as illustrated in this figure, during which time roller 65 is supported by the dwell of the nadir portion, thus permitting bell crank 66, with which roller 65 is associated, to assume its clockwise extreme position, as is indicated in solid lines in Fig. 2. 10 When in this position, its upstanding arm 67 clears the extremity 27 of rail shift lever 25, permitting the latter to remain in its counterclockwise extremity.

When, on the other hand, shaft 37 is arrested 15 in its other position 180° from the just described position, the apex 64 of cam 62 registers under the roller 65, forcing the bell crank 66 into its counterclockwise extremity when its arm 67 engages the extremity 27 of lever 25, moving the latter into its clockwise extremity and shifting the rail 18 rightwardly against the tendencies of spring 22. When rail 18 is in its roman position, viz., leftward as illustrated in Fig. 2, the clearance 23 is sufficient to permit any matrix subsequently received into the assembling block to drop 25 beyond the extremity of rail 18 onto the lower rails 15 of assembling block 12, but when shiftable rail 18 is in its bold position, viz., its extreme rightward position, its ingress end is interposed 30 to block the descent of any subsequently received matrices. As illustrated in Fig. 3, this rail thereafter continues to support such matrices which are then slid leftwardly by the oncoming matrices, augmented in part by a star wheel 68 which 35 rotates at a low frequency and is provided especially for that purpose.

When, after a line of matrices has been assembled in the block 12, an elevator signal is received, the elevator 11 is raised from its 40 composing levels as illustrated in Figs. 2 and 6 to an upper level known as the casting level, whereat other mechanism operates to remove the assembled line and clear the block for the composition of another line of matrices. During 45 its upward movement, elevator 11 carries with it, in addition to the assembling block which is integrally formed therewith, the shiftable rail 18 and the lever 25 which is secured to the elevator at its pivotal point 26. A hooked portion which 50 is provided upon the ingress end of the rail 18 prevents the assembled matrices from slipping off during the ascent of the elevator. When the extremity 27 of lever 25 passes beyond the control of the upstanding arm 67 of bell crank 66, it 55 again becomes subjected to the influence of spring 22 which, when lever 25 has last been placed into the bold position, serves to urge it back into the roman position. Both lever 25 and rail 18 are then maintained in the roman 60 position during the transit of the elevator, and until it is returned to the assembling or composing level at which time the inclined surface 28, mentioned above, comes into engagement with the upper extremity of arm 67 when the latter, 65 pursuant to the last shifting signal, remains in its bold position, as illustrated in dotted lines in Fig. 2. The inclined surfaces of extremity 25 and upstanding arm 67 thereby act to restore the lever 25 and rail 18 to the same position as that 70 of bell crank 66, where it remains until altered by a subsequent and opposite selection.

Modification

In Fig. 6 is illustrated a modified form of shiftable rail structure as well as a modified operat-

ing apparatus. As in the preferred form, rail 18 is provided with a depending lug 21 to which is connected a spring 22 that normally tends to maintain it in leftward or roman position. The depending flange 69 of shiftable rail 18 in this 5 case, however, is provided with a sidewardly extending abutment 71 beveled rightwardly and downwardly at 72 and adapted to cooperate with a roller 73, carried by a second class lever 74, pivoted at 75. A link 76 connects a center point 10 of lever 74 with the extremity of an armature 77 which is associated with the operating magnet 78. The energizing circuit 79 of magnet 78 contains a pair of contacts 81 normally spring inclined to remain apart, but capable of being brought into 15 contacting relation upon engagement by the extremity of a centrally pivoted lever 82, the opposite end of which is engaged by the wedge shaped surface of a spring detent 83. The influence of detent 83 upon lever 82 tends to maintain it in 20 either of its two extreme positions, as indicated in solid and broken lines, while a pair of selectable bars 84 and 85, which may correspond to the selectable bars 45 and 46 of the preferred structure described above, serve to move it into 25 each of its positions. Each bar 84 or 85 is provided with an upstanding lug 86 which is high enough to engage its associated arm of lever 82, and upon being selected and moved forward in the direction indicated by arrow 87, bar 85 moves 30 lever 82 into its counterclockwise extremity, closing circuit 79 while bar 84 moves it into its clockwise extremity, opening the circuit.

In order to effect the delayed operation of 35 shiftable rail 18 in response to the selection of either bar 84 or 85, magnet 78 may be of the conventional slow release and slow operating type, so that when the circuit 79 is established, as well as when it is broken upon the selection of one or the other of the selectable bars, the armature 77 will be delayed in its response for a short interval, comparable to the delay introduced into the preferred modification described above by the reduction gearing of Fig. 4.

The inclined surface 72 of the depending portion 69 of rail 18 serves in a manner similar to the inclined surface 28 of lever 25 of Fig. 2; that is, during the upward travel of elevator 11, the abutment 71, coming out of range of engagement with roller 73, permits the rail 18 to come under 50 the influence of spring 22 and move leftwardly into roman position. This, of course, is not the case if, previous to the ascent of the elevator, the rail 18 is already in its roman or leftward position. 55

Operation

In operation, the rail shift mechanism of Figs. 1 to 5 performs as follows:

Shaft 29 operates the record reader mechanism 60 and in addition also constitutes the medium through which all of the operative motion is distributed to the various moving parts of the automatic control unit. Its continued rotation is conditioned upon the closure of circuit 33 and 65 the energization of magnet 32, at which time only, the clutch mechanism 31 is maintained in operative condition for connecting the driving and driven portions of shaft 29, as explained in the parent application. 70

During roman character composition, the rail shift mechanism is disposed as indicated in Fig. 2, viz., cam 62 having its nadir portion against bell crank roller 65 and permitting the latter to assume its clockwise extremity and rail 18 to 75

remain in its left-hand position so as to afford the clearance 23. When under this condition matrices are received in the ingress portion of block 12, they enter in vertical alignment with clearance 23, and, having no rail 18 to engage the lugs 16 thereof, the matrices descend to lower position and are supported by the inert rails 15 of side walls 13 and 14.

Each matrix 17 has two character impressions 88 and 89, Fig. 3, spaced apart a distance equal to the distance between rails 18 and 15, so that when supported upon rails 18, the character 89 registers in horizontal alignment with the mold casting level while when resting on rail 15 the character 88 registers at this level.

In order to receive the matrices in their upper or bold face position with the 89 characters in casting position, such as is illustrated by the right-hand matrices in Fig. 3, the ingress portion of rail 18 is moved to its right-hand extremity, filling in the space 23 and presenting the foremost portion of edge 19 so as to support lugs 16 of incoming matrices 17. It follows that when a matrix is received upon either level and is thereafter moved leftwardly by the reception of subsequent matrices in cooperation with the rotation of star wheel 68, that they continue to be maintained at the level at which they are received, sliding upon one or the other of rails 18 or 15.

When it is desired to receive matrices in the roman position, a bar 46 is selected by its associated signal and in moving leftwardly, Fig. 4, pursuant to its selective operation, the pawl 54 thereof trips bell crank 55, releasing the lug 57 of the driven portion 53 of clutch 47, and permitting the latter to engage the driving portion 61 thereof. Driven portion 53 then continues to rotate one-half revolution until it engages the slot 52 of bell crank 49, where it is again withdrawn. Meanwhile, however, it has consummated 180° of rotation and has thereby presented the apex 64 of cam 62 opposite roller 65 of bell crank 66, causing the latter to engage lever 25 and thrust it clockwise, thereby maintaining rail 18 in its right-hand position. Through gear train 39, 41, 43, and 44, shaft 37 is reduced in operating speed with respect to driving shaft 29 at an efficient ratio so that before a rail shift operation is fully consummated, the most remote or slowest descending matrix may have just enough time in which to be received in its proper preexisting assembling block rail condition. During the operation of the rail shift mechanism, the record reader is momentarily suspended from operation by reason of cam wheel 36, upon starting to move with cam 62, presenting its apices 35 out of engagement with the contacts 34. This deenergizes magnet 32 by opening the circuit 33, and permits clutch mechanism 31 to disengage the driven from the driving portions of a clutch which is located upon shaft 29. The parent application discloses the operation of shaft 29 and its clutch in greater detail. It should be noted that upon the selection of either bar 45 or 46, that rail 18 is caused to be pressed in one or the other of its positions in a positive and permanent manner, which position may thereafter prevail indefinitely.

If after rail 18 has been selected into its bold position as last described and thereafter elevator 11 is raised to the linecasting level, lever 25 comes out of engagement with bell crank 66 during transit, permitting rail 18, under the influence of spring 22, to assume its roman position,

but upon the return of elevator 11, the inclined surface 28 comes into engagement with the upstanding portion 67 of bell crank 66 and is cammed leftwardly and again assumes the bold position in conformity with the selected condition of the rail shift mechanism.

While this invention has been explained and described with reference to the particular illustrations of the accompanying drawings, it will be understood that numerous modifications and variations may be made therein without departing from the spirit or scope of the invention. It is therefore intended not to be limited to the details of the accompanying drawings nor to the foregoing specification, but to define the present invention in accordance with the hereinafter appended claims.

What is claimed is:

1. In a linecasting and composing machine, a 20 composing apparatus, in a matrix storage magazine including a plurality of matrices, means under the control of said apparatus for releasing said matrices, an assembling block for receiving said released matrices in two alternative positions, a selector located at the ingress portion of 25 said block for determining into which of said positions subsequently received matrices may be admitted, and an automatic control unit including means responsive to certain signals for controlling said apparatus, and means under the control 30 of other signals for moving said selector including a pair of coacting levers between said unit and said selector having cam engagement portions to assist in their realignment following a 35 movement of said assembling block.

2. In a selector mechanism, a plurality of parallelly positioned selectable elements, means for individually selecting and actuating each of said elements in accordance with a signal individual to it, and a circuit breaker pivotally supported 40 between adjoining ones of said elements and operative into its circuit closing condition upon selection of one of said adjoining elements and to its circuit opening condition upon the operation of the other of said adjoining elements.

3. The combination of a selector mechanism including a set of signal responsive elements, a pair of selectable bars each responsive to a peculiar setting of said elements, a switch operating lever pivotally supported between said bars, means for moving each of said bars upon their being selected, and means on said bars for engaging and moving said switch.

4. The combination of a selector mechanism including a pair of selectable elements, a shaft 55 comprising a driving portion and a driven portion, a clutch connecting said portions, means for disengaging said clutch in two radial positions, a clutch release lever under control of one of said elements for disengaging said clutch in one of 60 said positions, and a clutch release lever under control of the other of said elements for disengaging said clutch in the other of said positions.

5. In combination, a pair of individually selectable bars, a clutch comprising driving and driven 65 portions, a signal responsive mechanism for selecting each of said bars, means under the control of one of said bars for controlling said clutch in one position, and means under the control of the other of said bars for controlling said clutch in 70 another position.

6. In a linecasting and composing machine, an assembler elevator for receiving two-character matrices, a sensing mechanism responsive to code signals for initiating the performance of said 75

composing machine, means under the control of said mechanism for determining the level at which said matrices are assembled in said elevator including a shiftable rail, a lever for operating said rail, mechanical power means selected directly from one of two conditions established in said sensing mechanism, and means for momentarily suspending the performance of said sensing mechanism during the operation of said level determining means.

7. In a linecasting and composing machine, an assembler elevator for receiving two-character matrices, a mechanism including a set of sensing elements for setting up mechanical selecting conditions responsive to code signals for initiating the performance of said composing machine, means under the control of certain of said mechanical conditions for determining the level at which the matrices are to be assembled in said elevator comprising a shiftable rail, means for moving said rail, mechanical power means selected directly under the control of either of two of said mechanical conditions established in said sensing mechanism, and means for momentarily delaying the performance of said sensing mechanism during the movement of said level determining means.

8. In a linecasting and composing machine, an elevator movable between composing and casting levels, a matrix receiving block carried by said elevator, a preconditioning device in said block for determining either of two alternative positions in which subsequently received matrices may be positioned, and a slow release and slow

operating electromagnet for moving said preconditioning means for thereby deferring the response of said preconditioning means.

9. In a linecasting and composing machine, a shiftable assembler rail for determining the reception of subsequently released matrices, a pair of selectable bars, a train of mechanical elements for shifting said rail in accordance with the selective operation of one or the other of said bars, a set of code elements variously presentable for placing into selective condition either of said bars individually, a tape sensing mechanism for controlling the placement of said code elements, and means for disabling said tape sensing mechanism for a predetermined time interval following the selection of either of said bars and until the consummate performance of said rail.

10. In a linecasting and composing machine, an assembling block movable vertically for transporting assembled matrices to a delivery slide level, a shiftable receiving rail in said block for assuming alternative positions to accordingly determine the level at which released matrices are assembled during line composition, a power driven mechanism for controlling the movement of said rail into either of its alternative positions, and a linkage connecting said mechanism and said rail comprising a pair of severable levers having means under the control of one of said levers for effecting the movement of the other of said levers during descent of said assembly block for purpose of alignment.

LOUIS M. POTTS.

CERTIFICATE OF CORRECTION.

Patent No. 2,062,332.

December 1, 1936.

LOUIS M. POTTS.

It is hereby certified that error appears in the printed specification of the above numbered patent requiring correction as follows: Page 2, second column, line 33, for the word "slug" read lug; line 68, for "rotatioin" read rotation; page 5, second column, line 28, claim 10, for "severable" read separable; and that the said Letters Patent should be read with these corrections therein that the same may conform to the record of the case in the Patent Office.

Signed and sealed this 9th day of March, A. D. 1937.
